CLOTHES DRIER

Tom D. Ramey, Girard, Kans.

Application October 24, 1955, Serial No. 542,416

9 Claims. (Cl. 34—87)

This invention relates generally to clothes dryers and more particularly to a clothes drier adapted to use air heated by the gas or electric burner of a stove.

Clothes dryers of various types are known in the art and as a whole, are impractical for use by the great mass of home owners for a number of reasons. Among these are an excessive cost resulting from (1) elaborate installations requiring plumbing and electrical alterations and additions, and (2) poor drier design involving the use of unnecessary structural parts, and complicated controls; a lack of convenient operating space for the drier in the average home; and a lack of flexibility in use of the drier.

Accordingly, the chief object of the present invention is to provide an improved clothes drier which will obviate the above and other limitation of known driers.

Another important object of the present invention is to provide an improved clothes drier which may be placed on the top of any ordinary range to fully utilize its heat, by conduction and convection, whether it be a gas, electric or wood burning range.

A further important object of the present invention is to provide an improved clothes drier which has a minimum but adequate number of safety controls which function to positively prevent the scorching or burning of clothes, etc. being dried.

A still further important object is to provide a light weight portable clothes drier which will conform with and may be readily secured to the surface of a range or stove without marring the surface thereof.

Another object is to provide an economical clothes drier which requires no electrical or plumbing changes but may be plugged into the regular 110 volt house circuit, and will not take up any valuable space in the home.

Other objects and advantages of the invention will become apparent during the course of the following description.

In the drawings I have shown two embodiments of the invention. In this showing:

Figure 1 is a top plan view, parts being broken away, of the clothes drier comprising the invention;

Figure 2 is a front elevational view thereof;

Figure 3 is a vertical, longitudinal, sectional view thereof taken on the line 3—3 of Figure 1;

Figure 4 is a vertical, transverse sectional view thereof taken on the line 4—4 of Figure 3, parts being shown in elevation;

Figure 5 is a detail view showing the solenoid door latch in operative position holding the heat control door open;

Figure 6 is a front elevational view of the lint trap forming a part of the present invention;

Figure 7 is a plan view of the heat conductor comprising a part of the present invention;

Figure 8 is a schematic view of the electrical circuit.

Figure 9 is a plan view of a modification of the invention;

Figure 10 is a vertical, longitudinal, sectional view thereof taken on the line 10—10 of Figure 9; and

Figure 11 is a vertical, transverse, sectional view thereof taken on the line 11—11 of Figure 9.

- 5 Referring to the drawings, numeral 10 designates the clothes drier as a whole which includes a double insulated casing of sheet metal including a curved tumbler receiving portion and a vertical flue portion and provided with a plurality of supporting rubber feet 14.
- 10 As seen in Figures 2—4 inclusive, the bottom of the drier casing is provided at its right end with an elongated heat inlet opening 16 extending rearwardly so as to be above the front and rear burners of a range R.

A flue 17 is defined directly above the heat inlet opening 16 by the casing end wall 18, the front wall 19, a side inner wall 20 and an inclined portion of a rear inner wall 21. The top of the flue 17 includes an open, rearwardly directed grille 23.

The flue 17 is adapted to be closed by a heat control door 24 which is pivoted to the lower edge of the inner wall 20 by means of hinges 25, 26. The door 24 may be swung from the vertical position in which it closes the drying compartment to the flue closing position shown in Figure 3 by means of an exterior handle 27.

- 25 The door 24 is retained in its flue closing position (Figures 3—5 inclusive) by the notched end 28 of a solenoid 29 which is normally held in a retracted position in the wall 21 by means of a spring 30. When the circuit C is connected to a 110 v. source by the plug 32, 30 the solenoid is energized by the closing of a toggle switch 33 which is engaged by the door 24 as it reaches the flue closing position. The door is thus held in this position until the plug 32 is disconnected or until a thermobulb 34 mounted in the top of the drier compartment 35 acts to open the circuit C upon the reaching of a predetermined temperature at which the clothes in the drier might become scorched.

Upon the opening of the circuit, the spring 30 retracts the notched end 28 of the solenoid permitting the door 24 to drop away from the toggle switch 33 and close the drier compartment to the heated air from the range which air passes up the now open flue 17. An aluminum heat conductor 36 comprising a plurality of spaced, parallel, connected tubes 37 is positioned in the base of the drier 10 and extends from the end wall 18 over the heat inlet opening 16 and well into the drier compartment. The conductor 36 permits heat to be conducted from a range burner into the drier compartment to maintain the temperature high enough to continue drying of the clothes even though the heat control door 24 has dropped to the closed position.

The front wall 19 of the drier 10 is provided with a pivoted, access door 38 through which clothes to be dried are inserted. An open-ended, drum-type tumbler 40 is 55 rotatably mounted in the drier compartment in alignment with the door 38 by means of a shaft 42 passing through the inner rear wall 21 and journaled in a bearing 43 fixed on the rear wall 44 of the casing 10. A motor M is mounted in the upper right rear portion of the casing 10 60 on a bracket 45 and is drivably connected with a large pulley 46 fixed to the tumbler shaft 42 by drive belts 47, 48 acting through a pair of intermediate speed reduction pulleys 49, 50.

The tumbler 40 includes a rear perforate wall 52 and 65 a plurality of angularly spaced agitator blades 53 fixed to its inner circumference to effect a turning of the clothes in the tumbler. The entire circumference of the tumbler is provided with a plurality of air scoops 54 formed by stamping adjacent portions of the circumference outwardly with their openings extending in the clockwise direction of rotation of the tumbler.

As seen in Figure 3, the tumbler 40 is spaced from the outer curved wall of the drier 10 to form an air passage 55 which is divided at the top of the casing by an arcuate plate 56 which forms the lower wall of the moist air exhaust passage 57. The latter connects with the flue 17 by an opening 58 in the wall 20 and adjacent the opening is a vertically slidable lint trap 59 having a handle 64 which is thus readily removable for cleaning purposes.

The ends of the casing 10 are provided with pairs of adjustable straps 62 terminating in hooks 63 which are adapted to engage the edge flanges of the range R to hold the drier firmly in place during operation.

The operation of the drier 10 is believed to be apparent. The drier is secured on the range R as described with its flue opening 16 positioned over two adjacent burners and the plug 32 is connected with a 110 volt outlet to start rotation of the tumbler 40. The burners are now turned on and the heat therefrom passes up the flue 17 and out the grille 23.

Clothes may now be inserted into the tumbler 40 through the access door 38 and the heat control door 24 raised (Figure 3) by the handle 27 to close the flue 17 and cause the heat from the burners to pass into the drier chamber, the door being retained in the flue closing position by the notched end 28 of the now energized solenoid 29.

The warm air from the burners is inducted into the interior of the clockwise rotating tumbler 40 by means of the air scoops 54 on its periphery and passes out of the tumbler by means of the perforate rear wall 52. This warm, moist air is forced by the incoming dry air into the air passage 55 from where it passes into the exhaust passage 57, through the lint trap 59 and through the opening 58 and out of the exhaust grille 23. Thus, the clothes in the tumbler 40 are subjected to a continuous and gentle flow of warm, dry air.

Before the temperature in the drier reaches a point at which the clothes might scorch, the thermocbulb 34 opens all but the motor M part of the circuit C to de-energize the solenoid 29 and permit the temperature control door 24 to close the drying chamber and open the flue 17. The same holds true in case of power failure except that the motor position of the circuit C would also be deenergized.

With the drying chamber closed, the heat from the burners passes directly up the flue 17. However, the drying operation may continue as the tumbler 40 continues to rotate and heat is still furnished to the drying compartment by means of the aluminum heat conductor 36. When dry, one load of clothes may be removed from the tumbler 40 through the door 38 and another load of wet clothes inserted.

For convenience, the casing 10 is equipped with a mechanical bell-ringing timer 65 so as to signal when a predetermined drying period has elapsed. The timer is entirely independent electrically, of the circuit C and forms no part of the present invention.

The embodiment of the invention disclosed in Figures 9-11 inclusive is similar in most respects to that already described. However, a generally rectangular heating chamber or passageway 66 preferably of steel is horizontally arranged in the flue 17 directly over the area covered by the burner on the range to admit air from the exterior of the casing to the interior of the drying compartment. The interior of the passageway is provided with a plurality of spaced, staggered, baffle plates 67 so that a greater volume of air will be heated by actual contact with the baffles or the sides of the passageway 66.

The flue 17 is also provided with a plurality of spaced, staggered, baffle plates 68 so as to ensure a maximum of heat transfer from the products of combustion of the range burner to the passageway 66 during their passage up the flue. It will be noted that the products of com-

bustion are thus kept separate from the air to be heated and passed to the clothes drying compartment.

The motor M, in addition to rotating the tumbler 40 drives a fan or blower 69 positioned behind the lint trap 59 in the outlet end of an arcuate exhaust passage 60 which connects with the clothes drying compartment as at 63. The fan is of such size as to induce a steady, even flow of air into the casing through the heating chamber or passageway 66, through the clothes in the perforated tumbler 40, through the exhaust duct 60 and the lint trap 59 and out of the casing. The air scoops 54 are omitted from the tumbler and perforations substituted therefor or the tumbler may be formed of stainless steel mesh, etc.

It will be noted that it is impossible for the clothes to become scorched as failure of the motor M will stop both the rotation of the tumbler and the fan 69, the products of combustion from the range merely passing out the flue 17 without access to the drying compartment as before.

It will now be readily apparent that the driers comprising the present invention are simple in construction and safe and efficient in use, present no material storage problem and may be economically constructed and of long life in use.

It is to be understood that the forms of the invention herewith shown and described are to be taken as preferred examples of the same and that various changes in the shape, size and arrangement of parts may be resorted to without departing from the spirit of the invention or the scope of the subjoined claims.

I claim:

1. A portable clothes drier comprising a unitary casing adapted to be operatively positioned on a kitchen range, a partition mounted therein and dividing it into two compartments, a clothes receptacle rotatably mounted in one of said compartments, the other of said compartments comprising a flue open at its top and bottom for the passage of heated gases therethrough, heat exchange means in said flue, means forming a part of said casing for admitting gas over said heat exchange means and into said one compartment, and power means mounted in said casing for rotating said receptacle.

2. A device as recited in claim 1 wherein said admitting means comprises a door formed in said partition.

3. A device as recited in claim 1 wherein said admitting means comprises a duct including baffles extending through said flue from an outer wall to said partition.

4. A device as recited in claim 3 wherein a fan is mounted in said one compartment to exhaust air therefrom and is rotated by said power means to induce air through said duct into said one compartment.

5. A clothes drier comprising a portable unitary casing including a closed drying compartment and an open vertical flue adapted to be positioned over a burner of a range for the passage of heated gases therethrough, a closed receptacle rotatably mounted in said compartment, means forming a horizontal passageway through said flue for admitting air to be heated therein from the exterior of said casing to said compartment, and power means mounted in said casing for rotating said receptacle and operating a blower for inducing air through said passageway into said compartment.

6. A clothes drier comprising a portable, unitary casing including a clothes drying compartment and an open flue having a common wall therewith and adapted to be operatively positioned over a burner of a range, a clothes receptacle rotatably mounted in said compartment, a door pivoted to said common wall of said casing and adapted to alternately close said compartment and said flue to heated gases from said burner, power means mounted in said casing for rotating said receptacle, and heat conduction means positioned in said casing under said receptacle and extending over said burner to furnish additional heat to said receptacle.

7. A clothes drier comprising a portable, unitary casing including a clothes drying compartment and an open flue having a common wall therewith and adapted to be operatively positioned over a burner of a range, a clothes receptacle rotatably mounted in said compartment, a door pivoted to said common wall of said casing and adapted to alternately close said compartment and said flue to heated gases from said burner, power means mounted in said casing for rotating said receptacle, and heat conduction means positioned in said casing under said receptacle and extending over said burner to furnish heat to said receptacle when said door closes said compartment to said heated gases.

8. A clothes drier comprising a portable, unitary casing including a clothes drying compartment and an open flue having a common wall therewith and adapted to be operatively positioned over a burner of a range, a clothes receptacle rotatably mounted in said compartment, a door pivoted to said common wall of said casing and adapted to alternately close said compartment and said flue to heated gases from said burner, power means mounted in said casing for rotating said receptacle, and a solenoid mounted in said casing and operative to hold said door in flue closing position, said solenoid upon failure of said

power means being deenergized to release said door for movement by gravity to close compartment.

9. A clothes drier comprising a portable, unitary casing including a clothes drying compartment and an open flue having a common wall therewith and adapted to be operatively positioned over a burner of a range, a clothes receptacle rotatably mounted in said compartment, a door pivoted to said common wall of said casing and adapted to alternately close said compartment and said flue to heated gases from said burner, power means mounted in said casing for rotating said receptacle, said receptacle being spaced from said casing, and an arcuate plate fixed to said casing adjacent said receptacle and terminating in said flue to form a heated air exhaust passage with said casing.
